(57) **CLAIM**

The ornamental design for a treatment head for an ultrasound therapy device, as shown and described.

DESCRIPTION

FIG. 1 is a front perspective view of a first embodiment of a treatment head for an ultrasound therapy device in accordance with the present invention;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a front perspective view of a second embodiment of a treatment head for an ultrasound therapy device in accordance with the present invention;

FIG. 9 is a front elevation view thereof;

FIG. 10 is a rear elevation view thereof;

FIG. 11 is a left side elevation view thereof;

FIG. 12 is a right side elevation view thereof;

FIG. 13 is a top plan view thereof; and,

FIG. 14 is a bottom plan view thereof.

The broken lines showing in the drawings are for the purpose of illustrating environmental structure and form no part of the claimed design.
